UNITED STATES PATENT OFFICE

171,283

HANGER DEVICE

Maurice Kramer, New York, N. Y.

Application June 11, 1953, Serial No. 25,442

Term of patent 7 years

(Cl. D33—8)

To all whom it may concern:

Be it known that I, Maurice Kramer, a citizen of the United States and resident of New York in the county of New York, State of New York, have invented a new, original, and ornamental Design for a Hanger Device, of which the following is a specification, reference being had to the accompanying drawing, forming a part thereof, and of which:

Fig. 1 is a front elevational view of a hanger device showing my new design.

Figs. 2 and 3 are top plan and side elevational views, respectively, thereof, and

Fig. 4 is a side elevational view thereof on a

reduced scale, a towel being shown in dotted line for purposes of illustration.

I claim:

The ornamental design for a hanger device, as shown and described.

MAURICE KRAMER.
